UNITED STATES PATENT OFFICE

EDWARD ADAMS RICHARDSON, OF BETHLEHEM, PENNSYLVANIA

PROCESS OF PREPARING FUELS FOR USE

Application filed August 18, 1928. Serial No. 300,569.

My invention relates to a process of gasifying fuels for use in burners, stoves, furnaces, kilns, metallurgical processes, internal combustion engines, etc.

8 The object of my invention is to provide a process of gasifying fuels so as to prepare liquid fuels for use in an advantageous manner, my process being such as to permit suitable latitude in operating-pressures and temperatures, according to the different liquid fuels treated and the uses to which they are to be applied.

16 My invention involves the treatment of a liquid fuel in such a manner as to supply the same for use, as when about to be burned or oxidized, at temperatures and preferably pressures which are at or in the neighborhood of or above the critical temperature and pressure of the fuel. This applies, likewise, 20 to mixed fuels which may be used in accordance with my invention, as, for example, hydrocarbon fuels, such, for instance, as petroleum fuels, examples of which would be kerosene, gasoline, distillate, fuel oils, also 25 mixtures, as, for instance, mixtures containing benzol, or mixtures, containing alcohol, etc. The fuel, when prepared in accordance with my invention, does not require atomization, as in the case of a fuel supplied in the 30 form of a liquid, inasmuch as by supplying fuel in the neighborhood of the critical temperature and pressure thereof the cohesive forces between the particles have been overcome to such an extent that they will act like 35 a gas and mix with the air or other oxidizing agent very thoroughly and rapidly so that combustion will be assisted to the fullest possible extent. Also, the fuel prepared in accordance 40 with my invention, by reason of the pressure at which it is supplied for combustion purposes, will overcome any resistance or pressure necessary to be dealt with in the proper and adequate supply of the fuel for the particular use. Furthermore, the 45 temperature of the fuel is sufficiently high to materially accelerate the rate of combustion or metallurgical reduction in the process in which it is used. An important advantage, 50 furthermore, is that the final temperature after cooling by expansion, as in the appa-

ratus or process in which the gaseous fuel is used, may be controlled in considerable measure by heating to higher temperatures than otherwise necessary before such expansion. Also, the cooling of the charge in an 55 engine, as of the Diesel type, produced by the expansion of the injection air used to atomize the oil, may be done away with and the desired final temperature of the injected fuel may be made quite high, approaching the 60 point of autoignition of the fuel, by controlling the temperature of the gaseous fuel before injection into the engine. Again, the 65 supplying of the fuel in this manner in the uniform operation of the combustion apparatus or other installation, any sudden changes in volume which would occur 70 through the boiling of a liquid fuel are avoided.

75 In general, my invention is carried out by subjecting the liquid fuel to a temperature and pressure in the neighborhood of the critical temperature and pressure thereof, although either the temperature or pressure or both may be much higher than the critical temperature and pressure according to 80 the requirements of successful operation of the particular fuel-consuming devices, but not so high as to produce thermal decomposition 85 of the fuel, in case this will interfere with the satisfactory operation of the fuel consuming devices. Higher temperatures, for example, may be used with higher pressures, these pressures, when decomposition 90 does tend to take place, resulting in the production of denser molecules than at lower pressures with the same temperature, with the result that less carbon is thrown down than would otherwise be the case. However, 95 in general, a longer time is necessary for such reactions to occur than the time factors in my process. This decomposition is known in the oil refining industry as cracking. It is well known, however, that where cracking of the oil occurs in the form of a liquid, there is a greater production of liquid products and a smaller deposition of carbon than when the fuel is treated in the form of a vapor. In 100 accordance with my invention it is not one of the objects to produce cracked fuels and

any cracking, therefore, which occurs is purely incidental and not essential.

By the critical temperature and pressure herein referred to I mean the critical temperature and pressure in the significance in which these terms are ordinarily used with regard to different liquids. In other words, for each liquid there is a temperature and pressure at which the volume of the vapor which can be formed from the liquid is no greater than the volume of the liquid itself. This is the critical point to which I mean to refer, that is to say, the temperature and the least pressure sufficient to prevent the boiling of the liquid. In accordance with my invention it is generally desirable, and sometimes necessary, to use higher pressures than the critical pressure as the change in volume, in passing through the critical stage, is rather large. Also, in the case of fuels which are generally mixtures of liquid chemical compounds, there are, at times, other possible points of equilibrium between the liquid and vapor phases called plait points, due to the difference in composition of the vapor and the liquid, distinguished by the fact that an increase in the pressure of the vapor at such a point might produce a condensation of the liquid, which liquid, if the pressure is further increased, may be evaporated. In accordance with my invention I am particularly interested in producing a gas by a process in which the volume increases with the temperature without boiling and without physical change in going from the liquid to the vapor state, the pressure being sufficiently great under normal conditions to prevent any sudden or very rapid changes in volume with the temperature.

The critical temperatures, pressures and volumes for many different pure or nearly pure compounds are known and are available in the works of Landolt-Börnstein and the Physical Tables of the Smithsonian Institute, etc. In carrying out my invention, in case I use kerosene, for instance, as a fuel I may begin by assuming that the kerosene is pure octane, the critical pressure of which is 350 lbs. gage and the critical temperature about 570° F. In using a hypothetical fuel in accordance with my process, the fuel would be run up to a pressure of 400 lbs. per square inch and the temperature to 700° F. or higher, expanding the fuel in a jet burner or similar device. Such a large amount of expansion takes place in the burner as to promote effective mixing with the air and causing the air to be drawn into the furnace in an effective manner. There would be no danger of cracking the oil as a temperature of at least 800° F. must be reached before any cracking begins. In case such fuel were used in an injection type oil engine having a maximum compression pressure of about 450 lbs. per

square inch, the fuel would have to be run up to as high as 900 lbs. to secure satisfactory operation of the fuel valves and sufficiently rapid injection of the fuel. The temperature would be raised, accordingly, to insure the gas remaining dry after expansion to the 450 lbs. in the engine. Thus, if I should find it disadvantageous to allow condensation on expansion, my process permits me to avoid such condensation by raising the temperature of the gaseous fuel to an amount sufficient to insure dry gas after expansion. In the case of the kerosene we have been considering, a temperature of 700° F. is sufficient, as the temperature after expansion would still be above 570° F., which is the critical temperature.

Where using mixed fuels of varying composition, such as fuel oils, a temperature of between 850° and 1100° F. and pressure of 180 to 225 lbs. per square inch would be used by reason of the differing compositions of such fuels sold under the same general specifications. In the case of such mixed fuels I have found it possible to determine the temperature and pressure needed in the following way, although I have found that in the actual operation of my invention the desired temperatures and pressures which are the most satisfactory for the purposes required may be determined in connection with the actual tests as hereinafter described, and through actual tests on and adjustments of the apparatus when applied to the apparatus or process with which the gaseous fuel is to be used. The approximate critical temperatures and pressure may be determined in the following manner:

First, estimate the proportion by weight of the different components. Second, determine or write down the chemical formulas for the components present, and the molecular weight of each compound. Thirdly, taking the pounds per thousand pounds of fuel of each, divide by the molecular weight of the component. The resulting figure is the number of mols of the compound in 1,000 lbs. of fuel. Fourth, find the total number of mols of all components in the 1,000 lbs. of fuel by adding the mols of each component. Fifth, find the percentage which the mols of each component bear to this total.

The critical temperature of the mixture may be approximated by taking the absolute critical temperature of each component and multiplying it by the mol fraction for that component, adding all these partial temperatures for the absolute critical temperature of the mixture. Gases may be added to the fuels, if desired, and the properties of the resulting mixtures estimated on the same basis.

For determining the critical pressure, I proceed as follows: It is sufficient for most purposes to take the absolute critical pres-

sure of each component, multiply by the mol fraction of that component, and add all the partial pressures for the critical pressure of the mixture.

5 Another method of procedure which I shall not describe in detail is to determine the "a" and "b" coefficients in Van der Waal's equation for each component, which equation is

$$10 \quad \left(p + \frac{a}{v^2} \right) (v - b) = RT$$

and find by similar steps the values of "a" and "b" for the mixture. From the equations which may be found in any theoretical physics, the critical pressure and temperature may be calculated from these average coefficients. Other works on theoretical physics are available, which will give accurate methods for calculating the properties 15 of mixtures, of which Van der Waal's "Continuität des gasformigen und flüssigen Zustandes" is probably the best. The calculation of the exact values of "a" and "b" by theoretical methods is in general impossible. 20 however, owing to lack of data on some of the constants involved.

The method of experimental determination 25 of the critical point according to the definition requires filling partially several sealed glass containers of known volume with various quantities of the liquid mixture. The temperature is slowly raised. Those with too little liquid will boil as the temperature is raised. If the quantities are properly chosen, one or more of them will, as the critical temperature is reached, show a cloudy appearance throughout the whole tube when the critical point is reached, followed, at a slight increase in temperature, by an appearance 30 of nothing but gas. Or, as the heated vapor is cooled, it can be subjected at given temperatures to high pressure until a temperature is reached at which a cloudiness appears. The range of temperatures in which 35 cloudiness accompanies the application of pressure, may be quite large in the case of mixtures. A certain low temperature will eventually be reached at which there will be no cloudiness, but below which the liquid 40 will appear on continued reduction of volume. The true critical point may well be defined as the point on the isothermal curve at which the slope is zero when the coordinates are 45 pressure against volume, the isothermal used being that of highest temperature which will give such a slope.

In the case of pure ethyl alcohol, for example, its critical temperature is 517° K. (degrees kelvin or centigrade absolute) and its critical pressure 922 pounds per square inch. Its mol weight is 90. Water has a critical temperature of 647° K. and its critical pressure is 3,196 lbs. per square inch. The approximate critical points of ethyl alcohol containing 90% by weight of alcohol and 10%

by weight of water, therefore, could be determined in the following way. The mol weight of water is 18. There are 900 lbs. of alcohol, or 10 mols in the mixture, and 100 lbs. of water or 5.56 mols. The mol fraction of water is .322, that of alcohol .678. I should expect $.678 \times 517$ plus $.322 \times 647 = 559^\circ$ K., which is 515° F. Similarly, the critical pressure is $.678 \times 922$ plus $.322 \times 3196 = 1653$ lbs. per square inch. Reduced to gage pressure, I have 1638 lbs. per square inch. In other words, commercial alcohol may require a temperature range of from 515° F. to 610° F. in the different classes of apparatus in which it may be used, while pressures of 1600 to 2000 lbs. per square inch must be anticipated. Methyl alcohol will require somewhat higher pressures.

Pure benzol requires 520° F. and 765 lbs. per square inch (gage) at the critical point, which may run up to 620° F. and 1200 lbs. per square inch for certain purposes.

I can, also, at least roughly, plan my apparatus with a reasonable knowledge of the heat quantities, pressures, temperatures, jet energies, volumes, and the like for quite a range of cases which may arise in practice.

For instance, ample pumping capacity must be provided in any given gasifying process to permit of reaching any reasonable pressure in the neighborhood of the critical pressure which may be expected in using the fuels which may be gasified in the process. The heating surface required in the preheater will also vary considerably with the degree to which the fuel is heated above the critical point. I have made up a chart for estimating roughly the properties of gases in the neighborhood of or above the critical point. The pressures are given as fractions of the critical pressure, the temperatures as fractions of the critical temperature, and the volumes as fractions of the critical volume. All quantities apply to one equivalent mol of mixture. This number is obtained by dividing 1,000 lbs. by the number of mols in the mixture which for 90% alcohol is 10 alcohol + 5.5 $H_2O = 15.5$. For the case of alcohol above, it amounts to 64.3 lbs. Hence all quantities apply to 64.3 lbs. of commercial alcohol. The heat required, for instance, to raise the alcohol at constant pressure from .800 of the critical temperature in degrees absolute (975° F. absolute) or 320° F. to 100 110 115 120 125 130

1850 lbs. per square inch (1.12 times the critical pressure) and 610° F. (1.10 times the critical temperature) is 10,800 B. t. u. per mol at critical temperature $1,000^\circ$ F. absolute which reduces to 10,500 B. t. u. for the given critical temperature and one mol, or to 164 B. T. U. per lb. To this must be added the heat to raise the alcohol from 60° F. to 320° F., or not less than 180 B. t. u. more (specific heat assumed at .7). If any appreciable chemical dissociation should occur, these fig-

ures would have to be increased. If the gas were expanded down to the critical temperature, I follow the constant entropy line 10.00 down to the isothermal curve 1.00. As there is nearly 500 B. t. u. difference in heat capacity, or roughly 7.6 B. t. u. per lb., this amount of kinetic energy may be developed in an expansion nozzle. This provides quite a satisfactory amount of energy for inducting the necessary air for combustion in a burner, or for agitating the contents of an engine cylinder for producing more rapid mixing and combustion. The temperature of the expanded gas is still much higher than the particles atomized by air or steam, so that there will be less delay in starting combustion.

The density of 90% alcohol at about 60° F. is roughly .827. The critical density is roughly .333. The density at 610° F. and 1850 lbs. per square inch pressure is .333/2.35 or .142. The density after expansion is .333/3.07 or .109. The volumes per mol are roughly 1.21 cubic feet, 3.00 cubic feet, 7.05 cubic feet, 9.21 cubic feet for the different states above. Divide by 64.3 (mol weight) for the volumes per lb.

I shall next consider the amount of heat which can be transmitted to fluids under the pressures I anticipate, so that I may proportion the heating surface required in the heater with some degree of certainty. I find that the flow of heat between a gas and a metal surface is proportional to the specific heat of the gas, to the mean difference of temperature between the gas and the metal, and is a function of the ratio of weight of gas flowing to the free area through the tube, pipe coils, or the like, the function, according to Reynold's law, being of the form

$$A + B \frac{w_1}{a_1}$$

where A and B are constant, or nearly so, for a given fluid, w_1 is the weight rate of flow of the fluid, and a_1 is the free cross section area through the tube bank or tubes. B is roughly proportional to the specific heat of the gas. The same law holds for water and presumably for all fluids. Hence keeping these facts in mind, I may use such data as may be available on heat flow (Heat Transmission by Radiation, Conduction, and Convection, by R. Royds, edition of 1921, published in London by Constable and Company, Ltd., being a suitable authority), making use of the known or approximate value of the specific heat of the fuel as it flows through the heater, and design the heater on that basis.

While my invention is capable of being carried out in many different ways, I have shown only one type of apparatus for use in connection therewith in the accompanying drawings, in which—

Fig. 1 is a diagrammatic elevation, partly in section, of an apparatus which will be used in accordance with my invention;

Fig. 2 is a set of curves useful for approximating the desired pressures and temperatures used in my process, the amount of heat required, the energy available on adiabatic expansion, and the final pressures, volumes and temperatures after such expansions, information of value in adapting the process to its particular application, such curves to be used only when more exact data on the thermal properties of the fuels used is lacking.

Fig. 3 is a diagrammatic side elevation of the apparatus shown as connected to the boiler of a power plant;

Fig. 4 is a partial cross section of the heater tubes on line A—A showing the method of securing the necessary gas passage between tubes, for the products of combustion which heat the oil; and

Fig. 5 is a partial elevation of the tubes and spacers in Fig. 4 showing a method of holding them in place.

For example, in carrying out my invention for preparing kerosene, or, instead, fuel oil, if desired, for use in a fuel oil burner, I may proceed as follows:

In the accompanying drawings I have shown a fuel tank 1 which is preferably located below the level of the ground, the same being provided with a steam-heating coil 2 supplied with steam by a valved inlet pipe 3, a draw-off pipe and strap 4 being provided for conducting away the condensate from the steam. The heat from the steam is provided for the purpose of reducing the viscosity of the fuel, when necessary, so as to make it pump more easily. The kerosene is drawn off from the tank 1 by a pipe 5 by suction, said pipe 5 being connected with a triplex force pump 6 provided with tight and loose pulleys 7 and 8 for driving the same by any suitable source of power. The pump 6 puts the oil under pressure ranging from 200 to 400 lbs. per square inch gage. In the cases of coal tar distillates, or alcohols, much higher pressures will be required. The pump 6 delivers the oil under pressure through a pipe 9 having a hand-operated valve 10, and thence by a branched pipe 11 to a pair of headers 12 and 13 of a heater located in a heating and combustion chamber 14, which chamber is formed of refractory material and insulated substantially as shown, and is arranged so as to provide gas passages for the products of combustion through a series of heater tubes 16 and 17 connected to the headers 12 and 13, and a smokebox 18 which discharges into a stack 19. The heater tubes serve to raise the incoming oil to the desired temperature. A sufficiently large set of tubes 16 and 17 is provided for a unit, for example

70

105

110

115

120

125

130

72 tubes, capable of handling 3000 lbs. of oil per hour, alternate tubes being arranged to connect with the two headers 12 and 13, the alternating of the tubes being desirable 5 solely on account of the small spaces between tubes along the header which would result if all the tubes were led into one header. The set of tubes 16 and 17 pass longitudinally through the chamber 14, said 10 tubes having a series of vertical U-shaped turns 20 therein and finally terminating by being connected alternately to the two discharge headers 21 and 22. The whole series 15 of tubes 16 and 17 are connected together by channels or buckstays 23 and 24 with spacing blocks 23a suitably formed to fit the contour of the tubes as shown, at such places as may be required in the design of the gas passages to secure the necessary velocity of gases over 20 the tubes, the aforesaid blocks being held in place vertically by cross pieces 24a engaging the blocks, said cross pieces being firmly held in place, preferably by securely attaching them to the channels or buckstays 23 and 24 25 located on both sides of the bank of tubes, which latter are drawn together by through bolts 25 and 26, pressing the tubes firmly against the blocks 23a, thereby forming a rigid heater unit. The bolts 25 and 26 extend 30 through the channel members 23 and 24 at sufficiently frequent intervals to secure the desired rigidity, passing through the entire series or bank of tubes. Furthermore, suitable baffles, including two substantially 35 horizontal baffles 27 and 28 and two vertical baffles 29 and 30, are arranged to give the most effective flow of hot gases or products of combustion through the series of tubes 16 and 17. It will be noted that the two headers 40 21 and 22 are connected together by a passageway 31 so that they may both have communication with a vapor-discharge pipe 32 provided with a hand-valve 33 and thence with a fitting 34 having a branch pipe 35 controlled by a hand-valve 36 adapted to 45 bleed off some of the fuel to a discharge or burner nozzle 37 located inside of the firebox end of the chamber 14 beyond the baffle 30. The furnace at this point has an opening 50 38 for air, which opening is partly filled by a preliminary heater 39 designed to be supplied with liquid oil from a valved pipe 40 for the initial heating or starting of the apparatus.

55 The vaporized oil continues up the pipe 32 to a header box 41 having a thermometer 42 therein and a gooseneck 43 leading to a pressure gage 44. The fuel expansion may be watched by means of these pressure and temperature devices, and regulated according to them, the header box 41 being provided for this purpose with a shut-off valve 45 leading to a pipe 46 which is adapted to supply oil to a plurality of burners adapted to 60 heat any desired kind of power plant, as, for

example, a steam boiler 46a of any desired construction. Said header box 41 is also provided with a hand-valve 47 which controls the purging of the system of cool liquid and gas or air contained in the system and may 70 be used as an overflow for the gaseous fuel until the pressure and temperature are suitable for use in the burners or other devices fed by the pipe 46, said overflow being carried through a pipe 48 into the tank 1. A 75 breather pipe 48a on the tank 1 permits of the escape of any permanent gases and relieves any pressure generated by the heating of the tank contents. Where use of the purging line 48 may be required frequently, or 80 where large amounts may be purged, the length of the pipe 48 may be increased, and arranged in any desired manner, thereby increasing the pipe surface available for acting as a condenser by condensing the fuel 85 gases being returned to the tank. The sloping position of the pipe enables the pipe to drain in the direction of the tank 1.

In the operation of my process steam is 90 supplied to the coil 2 in the tank 1, if necessary. The starting burner 39 is lighted and the pump 6 is also started after opening the valve 10. Oil, vapor and trapped gases will vent back to the tank 1 freely until the system is purged, thereupon the valve 47 will 95 be partially closed, the pump 6 running slowly so as to secure the proper pressure in the system as indicated by the pressure gage 44. As soon as the temperature reaches the desired magnitude, as indicated by the thermometer 42, the valve 36 may be opened 100 gradually until the vapor at the burner 37 ignites, whereupon the burner 39 may be shut down by closing the valve 40. The valve 45 may now be opened slightly 105 and the valve 47 closed, the pump 6 speeded up, and the valves 45 and 36 opened to the extent necessary to maintain the temperature while furnishing the desired 110 amount of gaseous oil to the boiler burners or other devices to which the pipe 46 is connected. Further control of the apparatus is obtained from now on by speeding up or slowing down the pump 6, and varying the amount of oil reaching the burner 37 by controlling the valve 36, this being done so as to maintain the pressure registered by the pressure gage 44, and the temperature as registered by the thermometer 42 at the desired 115 values. Also, if desired, suitable heat insulation material 49 may be provided in clothing the part located within the heat combustion chamber 14, or, in fact, around any of the other parts wherever desired, especially all pipes carrying hot gas under 120 pressure. However, as a cooling effect in the pipe 48 is desired it would be undesirable to clothe the same with heat insulating material. Also, if desired, a heat insulating layer 50 may be provided in the floor of the 125

130

combustion chamber underneath the refractory lining, the whole being carried on a suitable foundation, as, for example, piers 51 and steel work 52, as shown, or direct on 5 the ground or incombustible floor.

It will, of course, be obvious that the above 10 described apparatus is only one form of the apparatus which may be used for carrying out the process contained in my invention, 10 and the various parts and arrangement of parts, including methods of control, are capable of wide variation to meet the conditions under which the apparatus is to be used.

It is recognized by physicists that a substance 15 existing above its critical temperature is, for that temperature or a higher one, a permanent gas. In view of the fact that I prefer to operate above the critical temperature of the fuel selected I have, in the foregoing description, referred to the fuel as "gaseous or gasified." However, since my invention is not limited to actually passing the critical temperature, as a slightly lower temperature will give results approximating 20 the preferred condition, and since the gasified fuel may drop below the critical temperature and become a vapor on expansion, I refer in the claims to "gas-like vapor" as covering the fuel in its condition at the point 25 of use, irrespective of whether at that time it is technically a gas or a vapor.

While I have described my invention above in detail I wish it to be understood that many changes may be made therein without departing 30 from the spirit of the same.

I claim:

1. The method of utilizing normally liquid fuels which comprises the steps of heating a liquid adapted to be used as a fuel to a 40 temperature substantially at least as high as the critical temperature thereof while maintaining it at a pressure of the order of the critical pressure thereof, conveying directly while in this condition to the apparatus controlling the consumption of the same and oxidizing the fuel while in the form of a gas-like vapor.

2. The method of utilizing normally liquid fuels which comprises the steps of heating a liquid fuel to a temperature substantially at least as high as its critical temperature but below that at which substantial thermal decomposition takes place while maintaining the pressure great enough to substantially 50 prevent boiling of the liquid, injecting the resulting gas-like vapor into a combustion chamber and burning the same.

3. The method of utilizing normally liquid fuels which comprises the steps of heating a liquid fuel to a temperature substantially above its critical temperature while preventing any sudden change in the rate of expansion for any small temperature increment during heating through the maintenance 60 of a suitable pressure, permitting the

resulting gas-like vapor to expand into a gas comprising free oxygen and burning the resulting mixture.

4. The method of utilizing normally liquid fuels comprising the steps of preatomizing by heating a liquid fuel to a temperature at least as high as the critical temperature while maintaining it at pressures sufficiently great to keep the density of approximately the order of that of a liquid, injecting into 70 a free oxygen containing gas and burning the resulting mixture.

5. The method of utilizing a liquid fuel which comprises the steps of heating a liquid fuel above the critical temperature thereof, while maintaining at a pressure great enough to substantially prevent boiling, permitting a portion of the resulting gas-like vapor to expand, utilizing the energy in the gas to cause the same to mix with gases containing free oxygen and burning the same. 80

6. The method of utilizing a fuel which comprises the steps of heating a liquid adapted to be used as a fuel to a temperature substantially at least as high as the critical temperature thereof, while maintaining it at a pressure of the order of the critical pressure thereof and utilizing such fuel while in such condition for a reducing process. 90

7. The method of utilizing a fuel which comprises the steps of heating a liquid fuel to a temperature substantially at least as high as the critical temperature thereof, under a pressure substantially of the order of its critical pressure, conducting the resulting 100 gas-like vapor to the point of combustion and adjusting the pressure at the point of generation of the gas-like vapor to control the combustion of the fuel. 95

8. The method of utilizing a liquid fuel which comprises the steps of heating a liquid fuel rapidly to a temperature at least as high as approximately the critical temperature thereof and sufficient to cause undesirable thermal decomposition of the fuel on long 110 exposure, maintaining a pressure sufficient to maintain the fuel substantially liquid while below the critical temperature, and immediately burning the fuel heated to such temperature, whereby undesirable thermal 115 decomposition is substantially prevented.

In testimony that I claim the foregoing, I have hereunto set my hand this tenth day of August, 1928.

EDWARD ADAMS RICHARDSON.
